UNITED STATES PATENT OFFICE.

HERMAN C. HEATON, OF BERWYN, ILLINOIS.

RADIATOR VENT AND ALARM DEVICE.

Application filed December 5, 1919. Serial No. 342,784.

To all whom it may concern:

Be it known that I, HERMAN C. HEATON, a citizen of the United States, residing at Berwyn, in the county of Cook and State 5 of Illinois, have invented a certain new and useful Improvement in Radiator Vent and Alarm Devices, of which the following is a full, clear, concise, and exact description, reference being had to the accompanying 10 drawings, forming a part of this specification.

My invention relates to an improved radiator vent and alarm device.

The invention has general application to 15 the water cooling systems of internal combustion engines, more particularly of the type employed in pleasure and commercial automobiles, trucks, tractors, etc., and has as one of its main objects the provision of 20 an audible and visible alarm for indicating when the temperature of the cooling water has risen above a predetermined point. The feature of audibly sounding an alarm for informing the driver when the temperature 25 of the cooling medium has risen to an undesirable point has the pre-eminent advantage over prior methods of visibly indicating the temperature upon a thermometric device, of not requiring the attention of the driver, 30 and furthermore of positively informing him of the undesirable heating of the water at night when a thermometer on the radiator cap would be invisible. The emission 35 of steam vapor from the alarm device also affords a visible alarm which is noticeable instantly.

Another object of the present invention 40 is the provision of a non-spilling radiator vent for relieving the cooling system of any injurious pressure developed by the heating 45 of the cooling medium. This non-spilling vent performs the function of the ordinary overflow pipe as embodied in practically all water cooled cars of the present day, but without the wasteful loss of water or non-freezing solution that characterizes the latter.

My invention will be more apparent by 50 reference to the following specification, taken in connection with the accompanying drawings, in which:

Figure 1 is a fragmentary side elevational view of the front end of an automobile illustrating the combined vent and alarm device applied to the radiator.

Figure 2 is an enlarged detail view of

the alarm whistle, and the valve for controlling the connection of the vent therewith, and

Figure 3 is an isolated view of a modified arrangement of alarm device.

The cooling system for the internal combustion engine 1 is illustrated as being of the forced circulation type, the arrangement and operation of which is so well known as not to require an extensive or detail description of the same. The cold water is pumped into the cylinder jacket from the circulating pump 2, which draws the water from the bottom of the radiator 3 through the pipe 4. After circulating through the water jacket and performing its function of cooling the cylinders, the heated water flows up into the water manifold 5 from whence it is discharged into the upper water box 6 of the radiator 3. The cooling action of the radiator 3 is augmented by the forced circulation of air therethrough through the operation of the fan 7. Shutter mechanism, manually operable from the dash, for controlling the air circulation through the radiator may be provided if desired. Though the present embodiment illustrates the device as applied to a forced circulation cooling system, it is to be understood that the device also has application to the thermo-siphon system, and with perhaps a greater measure of utility, owing to the fact that these systems are subject to a quick rise in temperature by the falling of the water level below the circulation point.

The vent for the radiator comprises a pipe or tube 8 of relatively small bore which projects through the rear wall of the upper water box 6, in which the pipe is soldered or otherwise suitably secured. The vent pipe 8 enters the water box at a relatively high point, to one side of the flexible coupling 9, and has its end projecting horizontally into the water box, terminating in the central part thereof as indicated at 11. From the radiator 3, the vent pipe 8 is extended back substantially horizontally over the top of the engine 1 and is extended through the dash 12 into the driver's compartment. Here the vent pipe threads into a three-way valve or cock 13 of any preferred construction which, as shown in Figure 2, is adapted to place the vent pipe 8 in communication with either the upper alarm pipe 14 or the lower discharge pipe 15 through the rotatable valve passage 16.

The upper pipe 14 is connected to an alarm whistle 17, and is extended up to support the alarm whistle 17 in a plane preferably at a higher level than that of the filler cap 18 on the radiator 3. This alarm whistle may be of any suitable type having the ability to emit a quickly perceptible and characteristic sound, even under the slight steam pressure available in the vent pipe 8. The lower discharge pipe 15 extends down through the floor boards of the car and discharges beneath the vehicle.

It will be apparent that in the above arrangement of vent practically no loss of the cooling medium can result from the splashing of the same in the radiator. In prior arrangements employing overflow pipes extending down in the rear of the radiator there has always been a considerable loss of the cooling medium due to splashing of same into the overflow pipe resulting from the quick stopping or starting of the car, the jolting of the car, and the inclining of the car in traveling up and down steep hills. It will be seen that the likelihood of water splashing directly into the horizontally extending end of the vent pipe 11 is relatively remote, and even when this does occur the water simply pulsates back and forth in the vent pipe 8 until the same inclines downwardly, whereupon it runs back into the radiator again. The elevated position of the alarm whistle 17 prevents the discharge of the cooling medium except in cases where the expansion of the same is of such degree as to require relieving of the same. An excessive surplus of cooling medium in the system resulting from the expansion of the liquid can be readily relieved by turning the three-way cock 13 to discharge this surplus liquid down through the discharge pipe 15. The construction in the whistle 17 and in the relatively long horizontal vent pipe 8 prevents the rapid egress of air from the vent pipe and hence retards any liquid which might be splashed into the vent pipe from pulsating back and forth through the vent pipe.

Upon the generation of steam in the cooling system, due to overworking of the engine or through an insufficient quantity of water in the cooling system, the air and any water which may be entrained in the vent pipe 8 are expelled through the whistle 17 and the generated steam immediately sounds an alarm that the cooling water is at an undesirably high temperature by blowing through the whistle 17. The discharge of the vapor rising from the dash is also quickly noticeable so that a visible indication is given as well. If the sound of the whistle should prove annoying after the driver has been informed of the condition of the cooling system or if the steam issuing from the whistle should be obstructive of

the driver's vision, he can direct the steam down through the discharge pipe 15 by simply turning the three-way cock 13.

For the purpose of co-operating with the alarm whistle 17 to visibly indicate the height of water in the cooling system I have provided a gauge glass 20 mounted on the dash 12 and connecting with the water manifold 5 through the pipe 21. The combination of the alarm whistle 17 and the gauge glass 20 always keeps the driver informed of the two essential conditions in the cooling system, namely, the temperature of the liquid, and the quantity of the liquid in the system.

In the modified arrangement illustrated in Figure 3, a U shaped trap 22 is interposed in the vent pipe 8, having connection therewith through small chambers 23-23. A column of mercury or the like 24 is contained in this trap and functions to seal off the interior of the radiator or the cooling system from the alarm device. Upon the generation of an appreciable pressure of steam in the radiator the pressure overcomes the equilibrium of the mercury column and partly or entirely displaces it into one of the chambers 23, which are each of sufficient capacity to receive all of the mercury in the trap without allowing its entrance into the vent pipe connection.

After the mercury column has been discharged into the chamber 23 the steam pressure discharges through the body of mercury and escapes through the vent pipe 8, thereby blowing the alarm whistle. As soon as the pressure subsides the mercury flows back into the trap 22. The particular utility of the mercury trap is to entirely close off the radiator from the atmosphere to prevent all leakage and evaporation of the water or cooling compound and thereby avoid frequent refilling. Furthermore, the mercury trap, by requiring an appreciable steam pressure for its penetration avoids the objectionable blowing of the whistle from a slight expansion of air in the radiator or from the surging of water back and forth in the radiator or through the vent connection. It will be noted that although the mercury trap closes off the interior of the radiator for all practical purposes, it has an expansible action for relieving any excessive pressures in the cooling system.

I claim:—

1. In combination, an automobile radiator, a vent passage extending horizontally back from said radiator to prevent spilling due to a forward surge of the contents of said radiator, and a whistle connected to the rear end of said vent passage, said vent passage extending down to serve as an overflow.

2. In combination, an internal combustion engine and a circulatory water cooling sys-

tem for cooling said engine, said cooling system being closed off from the atmosphere and comprising a pressure sensitive relieving device adapted to relieve excessive pressures developing in said cooling system, and means for indicating a variation of pressure influencing said pressure sensitive relieving device.

3. In combination, an automobile radiator, a vent pipe extending horizontally back from said radiator, and a whistle connected to the rear end of said vent pipe, said vent pipe having a downwardly directed U-shaped depression intermediate its length forming a liquid trap.

4. In an automobile, the combination of an internal combustion engine, and a circulatory water cooling system for cooling said engine, said water cooling system comprising a radiator, a vent pipe extending from said radiator to a point adjacent the dash of said automobile, an alarm whistle connected to said vent pipe and operable by the generation of steam in said water cooling system, and means adjacent the dash of said automobile for controlling the operation of said alarm whistle.

5. In an automobile, the combination of an internal combustion engine, a circulatory water cooling system for cooling said engine, said circulatory system comprising a radiator, a relatively long substantially horizontal vent pipe extending back from said radiator to a point adjacent the dash of said automobile, an alarm whistle adjacent the dash in the driver's compartment and connected to said vent pipe, a discharge pipe adapted to connect with said vent pipe and leading out of the driver's compartment and means for controlling the con-

nexion of said whistle and said discharge pipe with said vent pipe.

6. In an automobile, the combination of an internal combustion engine, a circulatory water cooling system for cooling said engine, said circulatory system comprising a radiator, a vent pipe extending back from said radiator to a point adjacent the dash of said automobile, an alarm whistle, a discharge connection, and valve means for controlling the communication of said vent pipe with either said alarm whistle or said discharge connection.

7. In an automobile, the combination of an internal combustion engine, a circulatory water cooling system for cooling said engine, said circulatory system comprising a radiator, a vent pipe projecting substantially horizontally into said radiator, said vent pipe extending back from said radiator to the dash of said automobile, an alarm whistle adjacent the dash, a discharge pipe leading out of the driver's compartment, valves for placing said vent pipe into communication with either said alarm whistle or said discharge pipe, and a gauge glass adjacent said whistle on said dash for indicating the level of the cooling medium in said circulatory system.

8. In combination, an internal combustion engine, a water cooling system for said engine comprising a radiator, a vent connection for said radiator, said vent connection being extended back to a point adjacent the dash of the automobile, and means for indicating a discharge flow through said vent connection.

In witness whereof I hereunto subscribe my name this 2nd day of December, 1919.

HERMAN C. HEATON.
